United States Patent Office.

CHARLES A. BIKLE, OF HAGERSTOWN, MARYLAND, ASSIGNOR TO
HIMSELF AND JOHN W. GARNER, OF SAME PLACE.

Letters Patent No. 93,586, dated August 10, 1869.

IMPROVEMENT IN GRAIN-SEPARATORS.

The Schedule referred to in these Letters Patent and making part of the same.

To all whom it may concern:

Be it known that I, CHARLES A. BIKLE, of Hagerstown, in the county of Washington, and State of Maryland, have invented a new and useful Improvement in Grain-Separators; and I do hereby declare that the following is a full and exact description thereof, reference being had to the accompanying drawings, and to the letters of reference marked thereon.

My invention consists chiefly of an arrangement for causing the blower of a fanning-mill to regulate itself, so as to force an equal current of air through the separator; and it also consists of a device for feeding the grain and chaff in an even sheet through the separator, and for giving the shoe a shaking motion.

In the accompanying drawings—

Figure 1 is a side perspective view of my machine.

Figure 2 is a vertical longitudinal section of the same.

Figure 3 is one of my sectors, detached.

My arrangement requires two of these sectors, connected by bars, between which are slots for the blast to pass through. The blast then strikes a board, which turns it downward in leaving the blower. The bars and board being nearly balanced by a weight on the opposite end of the sectors, and the blast through the slots increasing or diminishing in proportion to the speed of the fan, the reaction of the current causes the sectors to move in such a way as to render the blast of equal force.

In the drawings—

C C are the sectors, connected by the bars D.

The board F turns the blast downward, in the direction shown by the arrow, fig. 2.

The sectors are pivoted at c c, and are connected, by the projection I and the link H, with the register A B, so that the vibration of the sectors shall open or

close the register, and thus regulate the amount of air admitted to the fan-case.

G is the bar on the outside end of the sectors, carrying the counterpoise K.

By this arrangement, the increase of the speed of the fan increases the force of the air upon the boards D, moving them and the sectors downward, and thus, through the links H, closing the register and regulating the blast.

As the blast becomes weaker, the sectors swing back, by means of the weighted bar G, and thus the register is immediately opened.

By this means, the blast is kept constantly the same, whatever may be the speed of the blower.

The weight upon the bar G may be increased or diminished at pleasure, so that the blast can be regulated to suit all kinds of grain.

For the purpose of feeding the grain and chaff in an even sheet to the separator, I employ a metallic toothed roller, L, which causes the chaff, &c., to spread in an even manner over the riddles or other devices, and also gives the shoe N a shaking motion.

Having thus fully described my invention,

What I claim, is—

1. The pivoted sectors C, provided with bars D, and the slots E, or their equivalent devices, for regulating the register and blast, substantially as set forth.

2. The above, in combination with the board F and weighted arms of the sectors, or bar G, substantially as set forth.

3. The peculiar construction of the toothed roller L, for separating the chaff, substantially as described.

CHARLES A. BIKLE.
